UNITED STATES PATENT OFFICE.

GEORGE R. WEST, OF WILKINSBURG, PENNSYLVANIA.

DESIGN FOR A PLATE.

SPECIFICATION forming part of Design No. 36,030, dated August 26, 1902.

Application filed February 18, 1902. Serial No. 94,700. Term of patent 3½ years.

To all whom it may concern:

Be it known that I, GEORGE R. WEST, a citizen of the United States, residing at Wilkinsburg, in the county of Allegheny and State of Pennsylvania, have invented a new, original, and ornamental Design for a Plate, of which the following is a specification, reference being had to the accompanying drawing, forming a part thereof.

As shown in the drawing, the leading or material feature of my design is the configuration of the border or edge of a plate or plaque. The figure of a rabbit 1 in a crouching attitude forms a part of the border, and the remainder is made up of representations

of horseshoes 2 and clover-leaves 3, arranged alternately.

It is apparent that this design is also applicable to plaques and other similar articles.

Having described my invention, what I claim as new, and desire to secure by Letters Patent, is—

The ornamental design for a plate, as herein shown and described.

In testimony whereof I have hereunto set my hand.

GEORGE R. WEST.
